UNITED STATES PATENT OFFICE.

OMER J. DANSEREAU, OF CLAREMONT, NEW HAMPSHIRE, ASSIGNOR TO SULLIVAN MACHINERY COMPANY, A CORPORATION OF MASSACHUSETTS.

BROACHING MACHINE.

Application filed August 31, 1921. Serial No. 497,349.

My invention relates to broaching machines.

An object of my invention is to provide an improved broaching machine. Another object of my invention is to provide an improved mechanically driven broaching machine in which a broach may be simultaneously pushed and pulled through the work piece. Another object of my invention is to provide an improved mechanically driven broaching machine of a type in which the broach may be simultaneously pushed and pulled and the force of the push and the pull equally divided automatically. A still further object of my invention is to provide improved control mechanism cooperating with a broaching machine of the improved type disclosed herein.

In the accompanying drawings I have shown for purposes of illustration, two forms which my invention may assume in practice.

In these drawings,—

Fig. 1 is a view partially in elevation and partially in section, the section being a central vertical longitudinal one through one form of my improved broaching mechanism.

Fig. 2 is a plan view with parts broken away of the same mechanism.

Fig. 3 is a view similar to Fig. 1 of another illustrative embodiment of my improved broaching mechanism.

Fig. 4 is a plan view of the broaching mechanism shown in Fig. 3.

Fig. 5 is a transverse section on the plane 5-5 of Fig. 3.

Fig. 6 is a detail on an enlarged scale of the portion of the controlling mechanism.

Fig. 7 is another detail of the mechanism partially in elevation and partially in section, showing further features of the control mechanism.

It has been discovered that the breakage in broaches may be largely reduced by pushing and pulling the broach simultaneously, i. e. by applying the force which is to effect longitudinal movement of the broach to the opposite ends thereof, but in the same direction whereby the broach may be relieved of either an excessive pull or an excessive push.

In my prior co-pending application filed June 8, 1921, Serial No. 475,893, I have disclosed a mechanism for automatically substantially equally pushing and pulling upon

a broach. For the purpose of avoiding the necessity for using a fluid under pressure to operate the broach, I have devised the mechanisms disclosed herein.

In the illustrative form of my invention shown in Figs. 1 and 2 the same comprises a main frame 1 provided with a pair of standards or hangers at each end, respectively numbered 2, 3 and 2' and 3'. In each of said standards are mounted journal members 4 which members serve as bearings for a pair of longitudinally movable feed screws 5 and 6, these screws being slidable through the journal members 4. Mounted upon and cooperating with the feed screws 5 and 6 and journaled in the journal members 4 are rotary nuts 7 and 8 cooperating with the feed screws 5 and 6 respectively, these nuts having slidably splined thereto members having clutch teeth 9 at opposite sides thereof and central peripheral grooves 10 cooperating with shifter arms 11 hereafter more fully described. Journaled upon each of the journal members 4 are pinions 13 and 14 and 13' and 14', these pinions being provided with clutch teeth 16, 17, 19 and 18 adapted to be engaged by the teeth 9 upon the members splined to the nuts 7 and 8. The screws 5 and 6 are provided with any suitable means for preventing their rotation, herein cross heads 20 and 21, respectively, guided in the frame 1. Each of these cross heads is provided with interchangeable means herein shown at 22 and 23 to cooperate with a broach 24 and respectively pull and push the same through a work piece W, it being evident that when the broach is to be pulled from left to right, the member 22 will cooperate with the cross head 20 while the member 23 cooperates with the cross head 21, and when the movement of the broach is in the opposite direction, the parts will be reversed. An abutment 25 intermediate between the standards 2 and 2' serves as a support for the work piece during the broaching operation.

Means is provided for driving the gears 13, 14 and 13', 14' comprising longitudinally disposed shafts 26 and 26' having keyed thereto gears 27, 28, 30 and 29 operating respectively in the driving of the gears 13, 14, 13' and 14', there being idlers 44 and 45 between the pinions 13 and 27 and 19 and 30,

respectively. The alined shafts 26 and 26' are driven by means of a differential 31 which is driven in turn by beveled gears 32 and 33 respectively, the latter of which is 5 driven by a motor 34.

It will thus be evident that when the load resisting the turning of the shafts 26 and 26' is equal, these shafts will turn at a uniform rate and that according to the well-known principle of the differential, that shaft which is the more heavily loaded will turn the slower while the speed of the other is accelerated proportionately, whereby equal driving forces will be automatically 15 imparted to opposite ends of the broach. For the purpose of shifting the clutches 9 to cause the driving of the gears 13, 14' or the gears 14, 13', I provide a control lever 35 connected by links 36 and 37 and push 20 rods 38, 39, pivoted levers 40 and 41, links 42 and 43 with the shifting arms 11 at the opposite ends of the machine.

The mode of operation of this mechanism will be readily apparent. Assume that the 25 lever 35 is swung to the right, it will be evident that the clutch teeth 9 will engage the teeth 19 and 16 and that as a result the nuts 7 and 8 will be rotated causing the broach to be simultaneously drawn and 30 forced through the work piece W, it being evident that by reason of the presence of the differential the force imparted in the form of a push and of a pull will be equally divided between the opposite ends of the 35 broach. When the broach has completely traversed the work piece, the lever 35 will be moved to mid-position, discontinuing the driving of the broach and upon placing of a work piece upon the opposite side of the 40 abutment and the reversal of the position of the broach and the members 22 and 23, a shifting of the lever 35 to the left will cause the broach to operate upon a work piece while moving in the opposite direction. 45 It will be readily apparent that in the case of a unidirectional motor the direction of rotation of the nut would need to be changed by some external means and this is accomplished by reason of the fact that the idlers 50 44 and 45 are provided between the gears 13 and 27 and 13' and 30.

In the form of my invention shown in Figs. 3 to 7, inclusive, I have disclosed a broaching machine operating on a similar, 55 but modified, principle and in which automatic means is provided for causing the broach to be drawn away from the pushing cross head after the broaching operation has been completed, thereby producing the 60 necessary space between the cross heads for the purpose of permitting a ready removal of the broach. In this mechanism the following broach controlling member automatically overtakes the broach in starting the 65 cut in the same manner as occurs in the first

described form of my invention. In this form of my invention the same is shown mounted upon a frame 50 having hangers 51, 52, 53 and 54 mounted thereon, the first two hangers being disposed at one end and 70 the second at the other end of the frame 50. Journalized in the hangers are rotatable nuts 55 and 56, these nuts being respectively provided with driving gears 57 and 58 keyed thereon. The gear 57 is provided with a 75 braking surface 59 and a similar braking surface or ring 60 is provided on the gear 58. Cooperating with the surfaces 59 and 60 are brake bands 61 and 62, respectively, which are adapted to be applied by means 80 of cam sleeves 63 and rotatable cams 64, best shown in Fig. 5, the bands being arranged to be slackened by a spring 65 when the cams are in the position shown in Fig. 5. Feed screws 67 and 68 are slidably mounted 85 in the hangers 51, 52 and 53, 54, respectively, these feed screws threadedly cooperating with the nuts 55 and 56 and being adapted to be fed simultaneously first in one direction and then in the other as the direction of rotation of the nuts is changed. Gears 69 and 70 mounted on shafts 71 and 72 mesh with the gears 57 and 58 and serve 90 to drive the latter. The shafts 71 and 72 are connected by a differential 73 driven by a gear 74 and a driving pinion 75 connected by way of a reversing mechanism 76 having an operating member 77 to a driving motor 78. The cams 64 are provided with arms 79 and 80, respectively, which arms are 95 provided with connections by means of vertical slots 81 with longitudinally movable rods 83 and 84 having collars 85 and 86 thereon. Cross heads 87 and 88 are guided by the frame and arranged at the adjacent 100 ends of the feed screws 67 and 68. These cross heads are provided, respectively, with latch mechanisms 89 and 90 adapted to operate with the collars 85 and 86.

The construction of these latch mechanisms is best shown in Fig. 7. Herein it will be noted that latches 91 are held in projected position by springs 92 and are retractable by thumb knobs 93. The rods 83 and 84 are normally held by springs 95 and 96 in a position to maintain the cams 63 and 64 in brake band slackening position.

The mode of operation of this mechanism will be readily apparent. Assume that the broach 100 is mounted between the cross 110 heads 87 and 88 by means similar to those shown in the first described form of my invention and that a work piece W rests against an abutment 25 and is ready to be broached; the lever 77 will then be shifted 115 in the proper direction to cause the shafts 71 and 72 to drive the gears 69 and 70 and also the gears 57 and 58 in such manner as to rotate the nuts 55 and 56 to cause the movement toward the right of the feed screws 67 120

and 68. By reason of the presence of the differential, the force imparted to the opposite ends of the broach will be equally divided into a push and a pull. The parts will 5 move toward the right from the position shown in Fig. 4, the right hand latch 91 sliding over the collar 85, and moving over rod 83 until the left hand latch 91 comes in contact with the collar 86. When this occurs the rod 84 will be pulled along with the 10 cross head 88 toward the right and so the arm 80 will be locked and by the cooperation of the cam 64 and the sleeve 63 the left hand brake band 62 will be caused to grip the 15 braking surface 60 on the gear 58. Accordingly, the movement of the left hand screw 68 will be retarded while the right hand screw 67 will be accelerated and the cross head 87 will move away from the cross head 88, although both may continue to move if the grip of the brake band 62 does not lock the gear 58. The collar 86 is so disposed as 20 not to be engaged by the latch 91 until the broaching operation is completed. It will 25 accordingly be apparent that by reason of the increased distance between the cross heads the broach may be readily removed and the parts interchanged to permit reverse movement of the broach. In order to 30 release the brake 62 it is simply necessary to lift the knob 93 and the rod 84 will then be moved to the left by the spring 96 and the brake band released.

The parts cooperating with the broach can 35 evidently be interchanged as previously described and the broach caused to make a cut during its opposite travel.

While I have in this application specifically described two forms which my invention 40 may assume in practice, it will be understood that these forms of the same are shown for purposes of illustration and that the invention may be embodied in various other forms without departing from its 45 spirit or the scope of the appended claims.

What I claim as new and desire to secure by Letters Patent is:

1. A broaching machine comprising a 50 broach, and mechanically actuated broach carrying means for passing said broach through a work piece including means for automatically equally mechanically distributing the working stresses throughout the broach.

2. A broaching machine comprising a 55 broach, and mechanically actuated broach carrying means for passing said broach through a work piece including differential means for automatically mechanically applying force simultaneously to both ends of said broach tending to impel it in one direction and maintaining said forces substantially equal.

3. A broaching machine comprising a 60 broach, and mechanically actuated broach

carrying means for passing said broach through a work piece including mechanical self-adjusting compensating means for distributing a constant degree of force to both ends of said broach simultaneously to impel 70 it in one direction.

4. In a machine tool of the type comprising an elongated cutter adapted to be moved axially through a work piece, the combination with said cutter of moving means therefor comprising mechanically driven heads engaging the opposite ends of said cutter, and driving means for said heads having a unitary initial drive element, and differential mechanism interposed between said 80 drive element and heads.

5. In a machine tool of the type comprising an elongated cutter adapted to be moved axially through a work piece, the combination with said cutter of moving means therefor comprising mechanically actuated means for exerting pull on said cutter to move it in the work, and complementary moving means for reducing the pulling stresses during work comprising means exerting a push 90 on said cutter and governing means operating automatically mechanically to vary the power delivered to said pushing and pulling means respectively.

6. A broaching machine comprising a 95 broach, feeding means adapted to maintain a working stress throughout said broach during its working stroke, and mechanically operated means automatically adapted to cooperate with said feeding means to render 100 ineffective a portion thereof upon completion of said stroke.

7. A broaching machine comprising a 105 broach, feeding means adapted to maintain a working stress throughout said broach during its working stroke, and means automatically to render ineffective a portion of said feeding means upon completion of said stroke including yielding controlling means.

8. A broaching machine comprising a 110 broach, feeding means adapted to maintain a working stress throughout said broach during its working stroke, and means automatically adapted to render ineffective a portion of said feeding means upon completion of said stroke including mechanically operated controlling means.

9. A broaching machine comprising a 115 broach, feeding means adapted to maintain a working stress throughout said broach during its working stroke, and means automatically adapted to render ineffective a portion of said feeding means upon completion of said stroke including automatically operated controlling means.

10. In a broaching mechanism, a plurality of aligned screws, means for attaching a broach thereto, and means for moving said screws simultaneously in the same direction.

11. In a broaching mechanism, a plurality 120

of alined screws, means for attaching a broach thereto, means cooperating with said screws to effect feeding movements thereof, and means for imparting equal driving forces to said second mentioned means.

12. In a broaching mechanism, a plurality of alined screws, means for attaching a broach thereto, and means including a differential for driving said screws.

13. In a broaching mechanism, a broach, a plurality of feed screws disposed with their axes parallel to a line parallel to the axis of said broach, means for connecting said screws to said broach, and means for causing said screws to share equally in the transmission of movement of said broach.

14. In a broaching mechanism, a broach, a plurality of feed screws, means whereby either end of said broach may be connected to either of said screws, and driving means for said feed screws.

15. In a broaching mechanism, a broach, a plurality of feed screws having their axes parallel to a line parallel to the axis of said broach, and means including a differential for driving said screws.

16. In a broaching machine, a broach, a pair of feed screws in alinement with said broach, connections between adjacent ends of said feed screws and said broach, nuts cooperating with said feed screws, alined shafts driving said nuts, a differential disposed between and connecting said alined shafts and driving means for said differential.

17. In a broaching machine, a broach, a pair of feed screws in alinement with said broach, connections between adjacent ends of said feed screws and said broach, nuts cooperating with said feed screws, alined shafts driving said nuts, a differential disposed between and connecting said alined shafts, driving means for said differential, and means controlled by the movements of said feed screws to automatically release one end of said broach when the broaching operation is completed.

18. In a broaching machine, a broach, a pair of feed screws in alinement with said broach, connections between adjacent ends of said screws and the ends of said broach, nuts cooperating with said feed screws, braking means adapted to cooperate with said nuts, driving means for said nuts, and means controlled by the movements of said screws for controlling said braking means.

19. In a broaching machine, a broach, a pair of feed screws in alinement with said broach, connections between adjacent ends of said screws and the ends of said broach, nuts cooperating with said feed screws, braking means adapted to cooperate with said nuts, driving means for said nuts, and means automatically controlled by the move-

ments of said screws for actuating one of said braking means at the end of the broaching operation, and manual means for releasing said braking means.

20. In a broaching machine, a broach, a pair of feed screws in alinement with said broach, reversible connections between adjacent ends of said screws and the ends of said broach, nuts cooperating with said feed screws, braking means adapted to cooperate with said nuts, driving means for said nuts, and a plurality of means controlled by the movements of said screws for separately controlling said braking means.

21. A machine tool having a movable tool, and mechanical means for effecting its movement comprising a plurality of normally linearly movable holding members therefor, and unitary means for actuating both members including means for imparting either relative movement or simultaneous equal movement in the same direction thereto.

22. A hole forming mechanism comprising a movable tool, and means for effecting its movement comprising a plurality of holding members having axially alined actuating screws adapted to have either simultaneous equal movement in the same direction or longitudinal movement relative to each other and unitary means for actuating both screws.

23. A machine tool having a work performing member, means for actuating the same including a plurality of threaded feed shafts, and means adapted to move one of said shafts automatically longitudinally toward the other upon the application of power to said shafts.

24. A machine tool having a work performing member, means for actuating the same including a plurality of threaded feed shafts, and means adapted automatically to move one of said shafts toward the other upon the application of power to said shafts and thereafter move the same simultaneously automatically, and movable means adapted to be braked automatically to effect further relative movement.

25. A machine tool having a work performing member, means for actuating the same including a plurality of threaded feed shafts one of which is adapted automatically to move toward the other upon the application of power to said shafts and both of which are adapted thereafter to move simultaneously automatically, movable means adapted to be braked automatically to effect further relative movement, and power equalizing means adapted to effect certain of said operations.

26. A machine tool comprising a work performing member, power transmission members, means for actuating the same to effect one operation of said work member,

and means to retard automatically an element of said actuating means to effect another operation of said member.

27. In combination, a tool, and means for feeding the same comprising a plurality of feed screws adapted to have longitudinal relative movement, and means whereby when one of said screws has reached its limit of travel the other will automatically have movement.

28. In a machine tool, a movable work performing member having a predetermined range of movement, actuating means therefore including a plurality of power propelled carriers, and means for automatically braking one of said carriers as its limit of movement is approached. 15

In testimony whereof I affix my signature.

OMER J. DANSEREAU.
